UNITED STATES PATENT OFFICE.

GARTH G. GILPIN, OF RIVERSIDE, ILLINOIS, ASSIGNOR TO UNION METAL PRODUCTS COMPANY, OF CHICAGO, ILLINOIS, A CORPORATION OF DELAWARE.

REENFORCING HOPPER DOOR FOR RAILWAY CARS.

Application filed August 14, 1925. Serial No. 50,224.

The invention relates to a railway dump car having a "door" forming a part of the car for retaining the load therein, which door is provided with hinges adjacent one of its sides and is capable of being "dropped" or swung open so that the load in discharging slides or passes over the upper surface of the door. Any means of raising the door to the closed position and any means for locking and releasing the door may be employed with my device.

A door for this purpose must be very strong and durable because:

First: It is part of the floor of the car and as such must sustain the load as well as the impact blow when the car is in motion.

Second: The car is frequently loaded from chutes or tipples from a height of ten feet or more, causing the load to be dropped directly upon the doors.

Third: Clam shell buckets are frequently used to unload such cars and it is not uncommon for these buckets to rest upon and drag over the doors.

Fourth: When the door suddenly comes to rest after being dropped, it is not only subject to a severe shock but it must sustain the severe impact thrust of the load which, of course, follows the door.

Fifth: As the load is theoretically equally distributed the door must be strong over its entire area and must be capable of transmitting the resulting strains to the car body without much deflection and no substantial distortion. Any bending of the door or drooping of the corners would cause a leak of the lading, especially of such fine material as sand, chats, etc. Any bending or warping might interfere with the complete closing and locking of the door.

The advantages of my door are applicable on any door of a freight car over which the lading moves when being discharged from the car, such as drop bottom general service cars (used in the drawings), hopper cars, swinging side doors or hopper bottom coal cars, etc.

In the drawings:

Fig. 1 is a portion of a railway car with my device applied thereto.

Fig. 2 is a section on line 2-2 of Fig. 1 portions being omitted to more clearly illustrate my invention.

Fig. 3 is a detail of the door braced according to my invention.

55

Fig. 4 is a side elevation of Fig. 3.

Fig. 5 is a section on line 5-5 of Fig. 3.

Fig. 6 shows a detail of a door with my corner reenforcement applied thereto.

Fig. 7 is an enlarged plan view of a corner of the door with my reenforcement.

Fig. 8 is a section on line 8-8 of Fig. 7.

Fig. 9 shows a modified form of the corner reenforcement wherein the web is spaced apart from the body of the door.

65

My device comprises a metal plate 1 (preferably steel) downwardly flanged at its sides (2-3) and reenforced with a pair of preferably corrugated reenforcements 4-5 which cross and overlap each other (6) 70 so that each reenforcement extends continuously between diagonally opposite corners of the door. This reenforcement strengthens the door to carry loads imposed upon it; not only by the additional stiffness obtained by the reenforcements, plus their corrugations, but also by the truss arrangement at the crossing where the straight reenforcement forms a strut for the offset reenforcement. The arrangement of reenforcements 80 also prevents the plate from buckling or bending, as any line of bend must cross at least one of the reenforcements.

It is old to form a metallic plate door with a continuous flange extending on all 85 sides of the door, i. e., with a flange extending continuously around the corner, as shown in Fig. 6, forming a so-called "solid corner" so as to strengthen the corner. My reenforcements are provided with a flange 7-8 90 at each side of their opposite ends which are secured to the flange of the door on either side of the corner by rivets 9-10, thus strengthening the door flanges against buckling or deflecting as vertical webs have 95 a tendency to do under load. The reenforcements are also preferably secured to the main body of the door as at 20. My arrangement prevents drooping of the corner of the door or, in other words, bending of 100 the door along lines parallel to 21-21 in Fig. 3. The corrugations, of course, assist in this reenforcement.

The flanged portion at the end of the reenforcement may be used to perform the 105 function of a continuous door flange so that

the door may be formed with separate flanges on each of its four sides, thereby making what is called an "open corner" as shown in Fig. 3. An open corner facilitates manufacture as it is not necessary to heat the plate to form it.

Figs. 6 to 9 inclusive show modifications wherein the construction is used to reenforce the corners of the door. The flange of this corner reenforcement may be used to perform the functions of the "solid corner" flange on the door as described above. This corner reenforcement is preferably secured to the door body, as at 11, and provided with a corrugation 12 or stiffening rib which substantially bisects the angle of the corner of the door and which preferably merges into the flange 13-14 of the corner reenforcement.

Fig. 9 shows a modification of this corner reenforcement wherein the flange 15-16 of the door projects downwardly and the flange of the corner reenforcement 13-14 projects upwardly so that the web 17 of the corner reenforcement is spaced apart from the main body 18 (or web) of the door, thus forming a box girder construction to resist the drooping of the corner of the door along lines parallel to 19-19 in Fig. 6. The web 17 then forms a direct tie to prevent the door flanges from buckling.

I have shown rivets securing the parts together but any other means, such as bolts or welding, may be used and still come within the scope of the invention.

I claim:

1. A metallic plate door comprising a panel with a flange at each side thereof, and a pair of reenforcements which cross each other and extend continuously between the diagonally opposite corners of the door and are secured to said panel; said reenforcements provided with a flange at each of their opposite ends secured to the adjacent flanges of the door.

2. A metallic plate door comprising a panel with a flange at each side thereof, and a pair of corrugated reenforcements which cross each other and extend continuously between the diagonally opposite corners of the door and are secured to said panel; said reenforcements provided with a flange at each of their opposite ends secured to the adjacent flanges of the door.

3. A metallic plate door comprising a panel with a continuous flange at the sides thereof, and a pair of reenforcements which cross each other and extend continuously between the diagonally opposite corners of the door and are secured to said panel; said reenforcements provided with a flange at each of their opposite ends secured to the continuous flange of the door.

4. A metallic plate door comprising a panel with a continuous flange at the sides

thereof, and a pair of corrugated reenforcements which cross each other and extend continuously between the diagonally opposite corners of the door and are secured to said panel, said reenforcements provided with a flange at each of their opposite ends secured to the continuous flange of the door.

5. In combination with a door for a railway car made of a metallic plate provided with flanges at its adjacent sides, and a corner reenforcement having a web portion and an integral flange at its adjacent sides secured to said door flanges, said web provided with an integral stiffening rib bisecting the angle of the door.

6. In combination with a door for a railway car made of a metallic plate provided with flanges at its adjacent sides, and a corner reenforcement having a web portion and an integral flange at its adjacent sides secured to said door flanges, said web provided with an integral stiffening rib bisecting the angle of the door, and merging into said flange.

7. In combination with a door for a railway car made of a metallic plate provided with downwardly projecting flanges at its adjacent sides, and a corner reenforcement having a web portion and an upwardly projecting integral flange at its adjacent sides secured to said door flanges, said web provided with an integral stiffening rib bisecting the angle of the door.

8. In combination with a door for a railway car made of a metallic plate provided with downwardly projecting flanges at its adjacent sides, and a corner reenforcement having a web portion and an upwardly projecting integral flange at its adjacent sides secured to said door flanges, said web provided with an integral stiffening rib bisecting the angle of the door and merging into said flange.

9. In combination with a door for a railway car made of a metallic plate provided with flanges at its adjacent sides, and a corner reenforcement having a web portion and an integral flange at its adjacent sides secured to said door flanges, said web provided with an integral stiffening rib bisecting the angle of the door.

10. In combination with a door for a railway car made of a metallic plate provided with flanges at its adjacent sides, and a corner reenforcement having a web portion and an integral flange at its adjacent sides secured to said door flanges, said web provided with an integral stiffening rib bisecting the angle of the door and merging into said flange.

11. A metallic plate door comprising a panel, and a pair of corrugated reenforcements which cross each other; said reenforcements and corrugations extending continuously between the diagonally opposite cor-

ners of the door and are secured to said panel.

12. A metallic plate door comprising a panel with a flange at each side thereof, and a pair of corrugated reenforcements which cross each other, said reenforcements and corrugations extending continuously between

the diagonally opposite corners of the door and are secured to said panel, said reenforcements provided with a flange at each of their opposite ends into which the corrugations merge and which is secured to the adjacent flanges of the door. ¹⁰

GARTH G. GILPIN.
